UNITED STATES PATENT OFFICE.

MATT CARAPINA AND FRANK NEVISTICH, OF TERRY, SOUTH DAKOTA.

RAIL JOINT.

Application filed January 31, 1922. Serial No. 533,036.

To all whom it may concern:

Be it known that we, MATT CARAPINA and FRANK NEVISTICH, citizens of the United States, residing at Terry, in the county of Lawrence and State of South Dakota, have invented new and useful Improvements in Rail Joints, of which the following is a specification.

The invention relates to improvements in rail joints.

The object of the present invention is to improve the construction of rail joints and to provide a simple, practical and efficient rail joint of strong, durable and comparatively inexpensive construction adapted to eliminate fish plates, angle bars and similar connecting means and capable of securely interlocking the contiguous ends of adjacent rails and of enabling the same to be securely spiked to the cross ties.

A further object of the invention is to provide a rail joint of this character equipped with male and female interlocking ends capable of effectually preventing lateral and longitudinal separation of the rails and of permitting the necessary expansion and contraction of the same and also enabling the rails to be readily separated and removed when the spikes are withdrawn.

With these and other objects in view the invention consists in the construction and novel combination and arrangement of parts hereinafter fully described, illustrated in the accompanying drawings and pointed out in the claim hereto appended, it being understood that various changes in the form, proportion and minor details of construction, within the scope of the claim, may be resorted to without departing from the spirit or sacrificing any of the advantages of the invention.

In the drawings, in which like characters of reference designate corresponding parts in the several views:

Figure 1 is a side elevation of a rail joint constructed in accordance with this invention.

Figure 2 is a central longitudinal sectional view of the same.

Figure 3 is a horizontal sectional view of the rail joint.

Figure 4 is a perspective view of the male section of the rail joint.

Figure 5 is a similar view of the female section of the rail joint.

In the accompanying drawing in which

is illustrated the preferred embodiment of the invention, the rail joint comprises in its construction male and female interlocking sections. The male section 1 consists of a rail of the standard configuration and provided with a laterally enlarged inwardly tapered web portion 2 presenting a vertical end face 3 arranged in flush relation with the end face of the head of the rail. The male section is provided centrally of the end of the enlarged web portion 2 with a longitudinal tongue 4 and it has an extended base 5 recessed at opposite sides of the tongue 4 and presenting broad bearing surfaces and forming shoulders 6 which are arranged in flush relation with the end face 3 of the laterally enlarged web portion 2. The tongue 4 which is arranged vertically, is provided at the top at its outer terminal with an upwardly projecting portion 7 arranged in spaced relation with the end face 3 of the laterally enlarged portion 2 to form an intervening recess 8 for interlocking with the female section as hereinafter fully described.

The female section consists of a rail 9 having its web 10 laterally enlarged at opposite sides at 11 at the end of the rail and the laterally enlarged portion 11, which is inwardly tapered, is provided in its lower portion with a longitudinal recess 12 arranged centrally of the end of the rail and extending upwardly from the bottom thereof and inwardly from the end of the same. The longitudinal recess 12, which receives the tongue 4 is provided at the top at the inner portion with a branch or socket 13 which receives the projection 7 of the tongue whereby the male and female sections are interlocked and held against relative longitudinal movement, sufficient space or play being provided in practice to permit the expansion and contraction of the rails. The base 14 of the female section 9 extends to the outer end of the laterally enlarged web portion 11, as shown, and is provided in its lower face with bottom recesses 15 located at opposite sides of the longitudinal recess 12 and presenting flat lower surfaces and inner shoulders 16. The flat faces of the recessed terminal portions of the base of the female section are fitted against the flat upper bearing surfaces of the extended portion of the base of the male section and the recessing of the base portions arranges the upper and lower faces of the bases of

the rails in substantially flush relation and provides an interfitting or interlocking connection, the shoulders 6 and 16 cooperating with the end faces of the male and female sections to limit the inward longitudinal movement of the rails.

The female section is adapted to be fitted over the tongue of the male section to interlock the parts and the interlocking of the parts will hold the sections against relative lateral and longitudinal movement and the spikes 17 for securing the male and female sections of the rails to the cross ties will hold the rails against upward movement so that the rails will be securely held in place without the employment of fish plates, angle bars and similar connecting means. Also the interlocked ends of the rails are arranged in overlapping relation so that the ends of the rails will be maintained in proper relative position to prevent the pounding of the wheels on the ends of the rails due to uneven spacing or positioning of the same.

25 Each of the rails is designed to be provided at each end with one of the male or female sections and one rail may be provided at one end with a female section and at the other end with a male section or both ends of one rail may be provided with a male section and each of the ends of the adjacent rail may be provided with a female section to permit interlocking of the rails.

What is claimed is:

35 A rail joint including a male section consisting of a rail provided with a laterally enlarged inwardly tapered web and having a central vertical longitudinal tongue extending from the end of the rail at the

bottom thereof and provided at the top 40 with an upwardly extending terminal projection, said male section being provided with an extended base recessed at the upper face at opposite sides of the tongue to form smooth flat bearing surfaces and to provide 45 inner shoulders, and an interlocking female section having a laterally enlarged inwardly tapered web provided in its lower portion with a longitudinal recess extending inwardly from the end of the female section 50 and upwardly from the lower face of the same to receive the said tongue and provided at the top at its inner portion with a vertical branch or socket receiving the terminal projection of the tongue to interlock the 55 sections against relative longitudinal movement, said longitudinal recess and tongue extending upwardly from the bottom of the rails and terminating short of the heads 60 of the same so as to leave the tread faces of the heads unbroken to the end of each rail, and said female section being also provided with extended base portions recessed at their lower faces at the bottom of the rail to form smooth unbroken surfaces and 65 fitted upon the flat bearing surfaces of the male section and forming inner shoulders, and the said web being tapered horizontally to provide a substantially elongated elliptical web formation at the joint and of a 70 width nearly equal to that of the head of the rails at the ends thereof and gradually decreasing in width to a point considerably beyond the end of each rail.

In testimony whereof we have hereunto 75 set our hand.

MATT CARAPINA
FRANK NEVISTICH.
